UNITED STATES PATENT OFFICE

163,969

FLUORESCENT LIGHTING FIXTURE WITH TRANSLUCENT LOUVER

Leslie K. Schoenbrod, Chicago, Ill.

Application August 18, 1949, Serial No. 4,596

Term of patent 14 years

(Cl. D48—23)

To all whom it may concern:

Be it known that I, Leslie K. Schoenbrod, a citizen of the United States of America, residing at Chicago, in the county of Cook, State of Illinois, have invented a new, original, and ornamental Design for Fluorescent Lighting Fixture With Translucent Louver, of which the following is a specification, reference being made to the accompanying drawing, forming part hereof, in which:

Fig. 1 is a top plan view of a fluorescent lighting fixture with translucent louver, embodying my new design; Fig. 2 is a bottom plan view; Fig. 3 is a side elevational view; Fig. 4 is an end elevational view of the same; and Fig. 5 is a fragmentary cross sectional view to a larger scale, taken on the line 5—5 of Fig. 1.

I claim:

The ornamental design for a fluorescent lighting fixture with translucent louver, substantially as shown.

LESLIE K. SCHOENBROD.
